UNITED STATES PATENT OFFICE.

WILLIAM H. AYER, OF CLAREMONT, NEW HAMPSHIRE.

PICKING-MOTION FOR LOOMS.

No. 872,781.

Specification of Letters Patent.

Patented Dec. 3, 1907.

Application filed July 12, 1906. Serial No. 325,835.

To all whom it may concern:

Be it known that I, WILLIAM H. AYER, a citizen of the United States, residing at Claremont, in the county of Sullivan and State of New Hampshire, have invented a certain new and useful Improvement in Picking-Motion for Looms, of which the following is a specification, reference being had therein to the accompanying drawing.

10 My invention relates to improvements in picker motion for looms and particularly applies to the mechanism constituting the picking motion thereof.

The object of the invention is to improve 15 the picking mechanism by providing novel features in the construction of the lug strap particularly, to render the same more durable in wear in conjunction with the picker staff; to provide novel means of adjustment be- 20 tween the picker arm and lug stick, and also novel adjusting mechanism between the picker arm and shoe or rock shaft; and to improve the general construction of this class of devices as will appear hereinafter.

25 With these objects in view the invention consists in certain novel features of construction and combinations and arrangements of parts as hereinafter described more fully pointed out in the claims, and as exemplified 30 in the accompanying drawings.

In the drawings I have shown one example of the complete physical embodiment of the invention, constructed according to the best mode I have so far devised for the practical, 35 application of the principle, and one modified form of a part of the invention.

Figure 1 shows as much of the mechanism of a loom as is necessary to illustrate the application of my invention thereto, and the 40 same is shown in operative position. Fig. 2 is a view taken at right angles to Fig. 1, showing the lug stick in section. Fig. 3 is a horizontal sectional view of the lug strap and a portion of the lug stick. Fig. 4 is an enlarged detail section illustrating the means for regulating the length of the lug stick. Fig. 5 is a modified form of the lug strap, shown in section, and, Fig. 6 is a view of a modified picker arm.

45 Referring to the drawings, the numeral 1 designates the frame of the loom; 2, the picker staff; 3 the pivot point of the staff supported in the rocker arm 4; 5, 5, support- 50 ing lugs secured to the frame; 6, the rock shaft journalized in said lugs; 7, a slid- 55 able block provided with a squared opening and

mounted on the shaft 6, and further pro- 60 vided with a set screw 8 by means of which screw the slidable block may be secured at adjusted points on the shaft; 9, the picker arm; 10, a bolt passed through the picker arm and also through a flange 11 on the block 7, and provided with a nut for securing 65 said flange and picker arm; 12, an offset or angular portion, forming a flange of the 70 picker arm and located at its lower end, and adapted to overhang the square rock shaft, as seen clearly in Fig. 4; 13, a set screw passed through a threaded opening in the flange 12 and bearing against the rock shaft; 14 a 75 lock nut on the screw 13; 15, an angular lug formed at the upper end of the picker arm and located parallel with the rock shaft; 16, the lug stick; 17, an opening in the end of the lug stick of a size sufficient to pass the 80 lug 15, and together with the lug forming the connection between the picker arm and the lug stick; 18, the lug strap; 19, slots formed near the inner ends of arms of the lug strap; 20, a bolt passed through said slots and also 85 through an opening in the end of the lug stick for forming the connection therebetween; 21, 21 are bands or straps of leather, bent to U-shape as shown, and in some instances provided with a metallic filling piece 90 22; 23, a wearing block preferably composed of layers of leather or any other suitable material and located in one end of the lug strap; 24, a bolt passed through openings in the lug strap and block, for securing the 95 block to the lug strap, and provided with a suitable nut, and 25 an opening in the lug strap to accommodate the picker staff.

In the modified form shown in Fig. 5 I omit the metallic filling piece in constructing 95 the lug strap and form the lug of a number of layers 26, preferably of leather, (but of course it will be understood that I may make this lug of layers of ticking, ducking, or in fact any material which would be suitable 100 for the purpose) and the block 27 in this instance is sewed to the lug strap, as represented by threads 28. I also reserve the right to dispense with the metallic filling piece when the wearing block is secured to 105 the lug strap or lug, by bolts or rivets.

By my construction of lug strap, the wearing block or roll will to a great degree relieve the lug strap from the accompanying bending and tearing motion caused by the motion 110 of the picker staff and throwing of the shuttle, and thus reduce the wear of the parts,

and consequently the expense of maintaining the machine. In the construction of the wearing block I preferably use leather, as I find this material to possess the best frictional qualities or properties, and when the block rides upon the picker staff, the friction is reduced to a minimum.

I do not wish to limit myself, however, to the exclusive use of leather in the construction of the wearing block, as other suitable materials may be found which will perform the service as well.

The connection between the lug stick and picker arm is extremely simple and yet very effective, as the stud or lug 15 is shaped to form a securing means as well as a bearing between the lug stick and picker arm. The lug stick is attached to the picker arm stud before connection to the machine, by inserting the extreme end of the stud through the opening in the lug stick and then permitting the picker arm to be lowered, then the lug stick is attached to the lug strap, and the upright portion of the stud prevents disconnection of the lug stick and the picker arm.

By manipulating the screw 13 in the flange 12, and with the screw bearing on the rock shaft, the upper end of the picker arm may be moved toward or away from the picker staff, the movement being on the bolt 10, as a center, and when the proper position is secured the connection may be made rigid by tightening up on bolt 10 by means of its nut.

In the modified form of picker arm illustrated in Fig. 6, the rock shaft 6^a is formed with a slotted enlarged portion in which the picker arm 9^a is held by bolt 10^a. When bolt 10^a is loosened the adjusting bolt 13^a may be turned to draw the picker arm away from the rock shaft 6^a, and to secure rigidity in the adjusted position the bolt 10^a is again tightened. A lug 15^a is also used on this picker arm 9^a. In the first instance, if the lug stick is accidentally broken, by removing the bolt 20, which fastens the strap to the stick, the stick may be readily disengaged from the picker arm by turning the lug stick off the lug 15 on the picker arm, and a new stick may be attached by a reverse procedure.

From the foregoing description taken in

connection with the drawings it becomes obvious that I have produced an improved mechanism which fulfills all the conditions set forth as the purpose and objects of my invention.

55

Alterations and changes may be made in the invention without departing from the spirit of the invention, as for instance in the modified form of lug strap I may dispense with the bolt and use threads for securing the block to the strap; I may also use the strap with or without the metallic filling piece; I may use the separate elements, of the invention, such as the picker arm or lug strap in combination with each other, or may supply 60 a machine with either of them separately.

Having thus fully described my invention, what I claim as new and desire to secure by Letters Patent is:

1. In a loom, and in combination, the 70 picker staff, lug stick and picker arm, an aperture near one end of the lug stick, an angular lug on the picker arm for engagement with said opening or aperture; a rock shaft, a 75 slideable block thereon and pivotally connected to said picker arm, and adjusting means on the picker arm adapted to bear on said shaft.

2. In a loom, and in combination, the 80 picker staff, lug stick, and picker arm, an opening in the lug stick and a stud on the picker arm engaging said opening; a rock shaft, a movable block on said shaft, a bolt 85 securing said block and picker arm, and a set screw in the picker arm bearing on said shaft.

3. In a loom, the combination with the rock shaft thereof, of a picker arm adjustably secured to said shaft, a lug stick removably secured to said picker arm, and a lug strap adjustably secured to said lug stick, said lug 90 strap comprising alternate layers of leather, a flat metallic filling piece and an outer layer of leather, and a bearing block sewed in the looped end of the strap.

In testimony whereof I affix my signature 95 in presence of two witnesses.

WILLIAM H. AYER.
